FLAME THROWER

Henry Sorensen, Ralston, Suffield, Alberta, Canada, assignor to Her Majesty the Queen in right of Canada as represented by the Minister of Defence

Filed Sept. 5, 1951, Ser. No. 245,233

Claims priority, application Canada Aug. 3, 1951
12 Claims. (Cl. 158—28)

The present invention relates to a flame thrower and more particularly to a flame thrower for use as a weapon to project a burning rod of flame fuel upon a target.

The flame thrower currently used by the Canadian Army is designated the "Wasp" flame thrower and is described in detail in Canadian Army Flame Training Manual, Flame Thrower Transportable, No. 2 Mark 2C (Wasp 2C) 1950, the principle of operation thereof being that thickened flame fuel is supplied under pressure to the flame thrower barrel which is provided at its forward end with a nozzle closed by a pintle valve formed on the front of a pintle running longitudinally through the barrel. The pintle is hollow and is formed in two sections which are capable of limited relative longitudinal movement with respect to each other. The rearmost section of the pintle is fixed to the body of the barrel and a supply of gas under pressure passes through the rear section of pintle and forces the front section thereof to a forward position where the pintle valve shuts off the nozzle at the front of the barrel of the flame thrower. To operate the gun the gas pressure is released from the rear section of pintle and the pressure of the flame fuel forces the forward section of the pintle to the rear, opening the nozzle and allowing the flame fuel to be projected as a rod of fuel under the influence of its own pressure. The rod of fuel is ignited by suitable ignition means timed to actuate upon opening of the pintle valve, and the stream of flaming fuel is cut off by restoring the gas pressure in the rear section of the pintle, forcing the pintle valve forward to close the nozzle of the flame thrower barrel.

The arrangement described in general terms above has proved fairly satisfactory in service but has a number of important disadvantages. In the first place, while the principle of operation is fairly simple, the pintle formed in two sections in the manner described, and its associated mounting, required a considerable number of accurately machined parts, making production of the flame thrower both costly, and time and labour consuming. In addition, of course, the maintenance of such weapons in action has required highly trained personnel.

More important from a tactical point of view, the "Wasp" flame gun has a limited range, and the rapidity of its operation is not as great as might be desired.

The present invention has, as one of its principal objects, the provision of a flame gun of simplified design which can be produced with a minimum of production time and cost, and which requires a minimum of maintenance and training of personnel for its operation.

It is also the object of this invention to provide a flame gun having an increased range and rapidity of operation.

Further objects and advantages of the invention will become apparent as the specification proceeds.

Broadly speaking, the foregoing objects of the invention are achieved by forming the pintle in such a manner that it functions as a single unit and providing an air cylinder mounted on the body of the flame thrower at the rear thereof, into which the rear portion of the pintle, which is formed as a piston to fit said cylinder, extends, so that the entire pintle moves as a single unit to control the flow of flame fuel. The whole structure of the pintle assembly is accordingly greatly simplified and the added advantage is achieved that the pintle itself may be made

2

considerably slenderer to provide much better flow characteristics in the barrel of the gun, and thus a greater range of projection has been achieved.

Gas under pressure to control the movement of the pintle valve may be supplied and controlled in a number of manner, but it is preferred to supply and control it by means of a control block assembly in which a control spindle may be slid longitudinally of its axis simultaneously to establish communication between the cylinder and the atmosphere, and to cut off communication between a supply of gas under pressure and the interior of the cylinder. Such an arrangement lends itself readily to coupling with a second longitudinally slideable spindle within the control block, which is arranged to be slid longitudinally to operate an electric micro-switch for actuating the ignition means, and a petrol control valve controlling flow of petrol to the ignition means, in which arrangement the two spindles may be simultaneously operated, and adjusted to provide for proper timing and sequence of the operations, whereby, the assembly being all connected to a single trigger, all operations of the flame thrower required to fire a shot will take place on pulling said trigger and will cease upon release of said trigger.

The invention will be more fully appreciated from the following detailed description of an embodiment thereof in which reference is had to the accompanying drawings wherein:

FIGURE 1 is a perspective view of a flame thrower according to the invention, fully assembled and ready for action,

FIGURE 2 is a sectional view taken along the longitudinal axis of the gun, showing the pintle valve in closed position,

FIGURE 3 is an enlarged detail partly in section, taken along the plane 3—3 in FIGURE 1,

FIGURE 4 is a horizontal section taken through the longitudinal axis of the gas cylinder at the rear of the flame thrower barrel, illustrating the position of the pintle piston when the pintle valve is in the closed position and illustrating the arrangement of the gas control valve,

FIGURE 5 is a top view partly in section of the ignition means used to ignite the main flow of flame fuel when the gun is fired,

FIGURE 6 is a perspective detail of the petrol nozzle, the section being taken along the plane 6—6 in FIGURE 7,

FIGURE 7 is a front view of the petrol nozzle, and FIGURE 8 is a perspective view partly cut away of the atomizer nozzle in the ignition means.

Referring more particularly to the drawings, a flame thrower according to the invention is generally of the same shape and external appearance as previous flame throwers and comprises the barrel 10 provided with the conical nozzle component 12 forming a valve seat 13 at the front end thereof and the nozzle tip 14.

The barrel 10 is screw-threaded and connects at 15 to the gun body 16 which is formed with the hollow elbow 17 of generally the same internal diameter as the barrel 10 and screw threaded as at 18 for connection in conventional manner to a supply (not shown) of flame fuel.

The body portion 16 is also provided with a rearwardly extending portion 19 corresponding in diameter to the barrel 10 and bored internally in axial alignment with the axis of the barrel to provide the boring 20. The rear end of the portion 19 is suitably screw-threaded and shouldered as at 21 to provide for the attachment thereto of the cylinder block 22 which is mounted in axial alignment with the boring 20 and the barrel 10. The cylinder block 22 is provided with a flange 23 which abuts against the rear face of a sealing ring 24 and sealer 24a and is secured in position by the securing ring 25 which is secured by screw-threads around the rear

of the portion 19 as will be best observed from FIGURE 4. Provision is made by means of the radial holes 26, the annular space 27 and the borings 28 for communication between the space 23' in the front end of the interior of the cylinder block 22 and the atmosphere.

Extending axially lengthwise of the barrel 10 is the pinte 29 which is thickened over the forward portion 30 thereof to provide a conical portion 31 at the front end which is of larger diameter at its base than the diameter of the nozzle tip 14, so that the rear portion 32 of the conical portion 31, when pressed forward, will seat against the forward portion 13 of the conical nozzle component 12 to form the pinte valve. Mounted upon the portion 30 of the pinte 29 and uniformly spaced about the circumference thereof are the pinte guide vanes 33. These are generally three in number, spaced at 120° to each other and are designed to keep the pinte 29 in axial alignment with the barrel 10 and associated nozzle parts 12 and 14. At the rear, pinte 29 is screw-threaded as at 34 to the pinte piston 35 which fits slidably within the boring 29 and is provided with the enlarged head 36 at its rearward end which forms a piston head slidable within the cylinder block 22. The head 36 is provided with a suitable sealer 37 secured to its rearward face by the securing screw 37a. Thus it will be observed that the pinte 29 and its connected parts are free to reciprocate to a limited extent within the barrel 10, the forward extent of such reciprocation being limited by the seating of the pinte valve in the valve seat formed by the valve seat portion 13 of the conical nozzle 12; a small free space is allowed for between piston head 36 and the ring 24, compressing the sealer 24a. The rearward extent of reciprocation of the pinte is limited by the end 38 of the gas cylinder 39 formed in the cylinder block 22. The rearward motion is usually further limited by placing within the gas cylinder 39 two hard fibre recoil washers 39a.

The body 16 is mounted upon a suitable mounting, which may for instance be on a weapon carrier or other vehicle, by being pivoted by pivot bolts 40 and 40a to the arms 41 of the stirrup 42 which is pivoted at its other end upon the pin 43 which is secured upon a securing bar 44 which in turn is secured by means of the slots 45 and securing screws 46 to a supporting structure. Thus the gun is pivotable in a substantially horizontal plane about the axis of the pin 43 and in a substantially vertical plane about the pivot bolts 40 and 40a.

The cylinder block 22 fits against a suitably curved side 47 of the control block 48. A passageway 49 is formed in the cylinder block 22 and the control block 48 is provided with a similar passageway 50 which is so arranged as to register with the passage 49 when control block 48 and cylinder block 22 are secured in position by means of the base plate 51 and the securing bolts 52, 52a, 53, 53a, 54, 55 and 56 which fit in suitable borings in the base plate, cylinder block and control block. A sealing ring is inserted where passage ways 49 and 50 join.

As will best be observed from FIGURE 4, the passage 50 in the control block widens out to form a valve cylinder 57 which is disposed substantially parallel to the axis of the gun. The control block 48 is tapped at one side thereof at 58 to secure the hollow plug 59 which connects to a supply of gas under pressure (not shown) by means of a flexible hose 60. The gas inlet port 58a affords communication between the interior of the hollow plug 59 and the interior of the valve cylinder bore 57. Slidably fitted within the cylinder bore 57 is the valve body 61 which, it will be observed, is centrally bored with the passage 62 but is closed at its forward end 63 which end is secured to, or formed integrally with, a control spindle 65. The valve cylinder bore 57 is provided with an enlarged portion 57a within which is screw-threaded the valve plug 66. This plug is hollow and is provided with the shoulders 67 which are arranged

10 to be in abutment with the forward face of the portion 63 which is provided with a neoprene seat, of the valve body 61 when the latter is in the forward position. At the forward end of plug 66, there is a boring 68 which is 5 a slidable fit around the control spindle 65 so that the latter is free to slide therein. A number of radial borings 69 establish communications between the atmosphere and the interior boring 70 of the valve plug 66. The rear of the valve body 61 is provided with a spring seat 71 and the compression spring 72 is compressed between the shoulder 73 and the shoulder 74 at the rear of the valve bore 57.

15 As will be seen most clearly from FIGURE 4, the valve body 61 is provided with the annular groove 75 which is arranged so that when the portion 63 of the valve body rests against the shoulders 67 of the valve plug 66, the groove 75 will register with the gas inlet port 58a, a number of radial borings 76 providing communication between the base of the groove 75 and the 20 hollow passage interior 62 of the valve body 61. Further it will be observed that there are a number of radial borings 77 near the front end of the valve body 61, establishing communication from the interior 62 thereof, to the annular space 78 between the walls of the enlarged portion 57a of the cylinder or bore 57, and the 25 exterior surface of the valve body 61.

30 It will be observed that, upon movement of the valve body 61 to the rear, communications is cut off between the gas supply and the gas cylinder 39 by reason of the groove 75 becoming out of register with the gas inlet port 58a. At the same time, however, communication is established between the gas cylinder 39 and the atmosphere through the passages 49 and 50, the interior 62 of the valve body 61, the radial borings 77, the space 78, 35 around the portion 63 and the hollow interior boring 70 of the valve plug 66 and radial borings 69 in the head thereof.

40 Secured to the rear of the base plate are the handle-bars 80 and 81 which terminate in the hand grips 82 and 83 respectively. Mounted in a suitable boring passing through the base plate 51 and the control block 48 is the trigger rod 84 in suitable position so that the bent-over end 85 thereof is in proximity to the hand grip 83, in appropriate position to be grasped by an operator. On the front end of the trigger rod 84 there is secured the arm 85' by means of the nut 86.

45 As can best be observed in FIGURE 3, the arm 85' has a screw-threaded boring at its free end into which is threaded the adjustable screw 87 which carries the lock nut 88. The end 89 of the adjustable screw is arranged to be in axial alignment with the end of the control spindle 65 so that axial movement of the trigger rod 84 will cause the end 89 of the screw 87 to push the control spindle 65 to the rear, cutting off communication 50 between the gas supply and the gas cylinder 39, and opening communication between the gas cylinder 39 and the atmosphere. Also secured to the trigger rod 84, for movement therewith is the connector piece 90 which is bored to provide a sliding fit around the micro-switch 55 actuating spindle 91 which fits slidably within the boring 92 in the base plate 51. The micro-switch actuating 60 ignition control spindle 91 is bored centrally to receive the petrol valve stem 93 and is further provided with the bevelled shoulder 94 which actuates the micro switch 65 95 upon movement to the rear thereof, to operate the electrical ignition. Mounted in tapped boring 97 a depending portion 96 of the control block 48 is the petrol 65 control valve body 98 provided with the rearwardly facing valve seat 99. This valve seat is formed from synthetic rubber or neoprene and is adapted to cooperate with the petrol valve head 100 which is secured to the end of the petrol valve stem 93. The tapping 101 and 70 petrol port 102 provide means for connecting the boring 97 to a supply of petrol under pressure (not shown). 75 The boring 97 is formed with a shoulder against which is

seated the sealing assembly 103 which is formed from a synthetic rubber sealer 104 and the two discs 105 and 106. The disk 105 is provided with a rearwardly facing annular rib 107 which aids the sealing action of the assembly to prevent escape of petrol to the rear. The sealing assembly 103 is held securely in position by means of the hollow plug 108 which is screw-threaded into the rearwardly tapped portion 109 of the boring 97. The plug 108 has an axial boring 110 which is a slideable fit around the petrol valve stem 93, and mounted on the valve stem and slideable with respect thereto inside the hollowed-out portion 111 of the plug 108, is the spring retaining washer 112. Surrounding the petrol valve stem 93 within the hollowed-out space 111 is the compression spring 113 having its forward face against the washer 112 and its rearward face against the shoulder 114 at the rear end of the hollowed-out space portion 111.

The rear end of the ignition control spindle is bored out as at 115 and the valve stem 93 extends centrally through said boring to extend beyond the rearmost face 116 of the micro-switch actuating control spindle 91, and is screw threaded at its extremity to provide for the mounting of the adjustment nuts 117 and 118. Mounted upon the rearward end of the petrol valve stem 93 is the compression spring 119 which is compressed between the nut 118 and the shoulder 120 in the bottom of the boring 115. The compression spring 119 is considerably weaker than the compression spring 113 and accordingly it will be observed that, as the micro-switch actuating ignition control spindle 91 is moved to the rear, it will merely compress the spring 119 until the face 116 contacts the nut 118 at which point the valve stem 93 will be drawn to the rear to unseat the valve head 100 from the valve seat 99. It will be observed, however, that the amount of movement of the ignition control spindle 91 which will take place before the valve stem 93 will be moved to open the petrol valve can be adjusted by adjusting the position of the nut 118 and its associated lock nut 117. In this manner the timing of the actuation of the micro switch 95 and the opening of the petrol valve may be correlated so that a spark is produced in the ignition device immediately before petrol commences to issue forth therefrom.

The forward end of the petrol control valve body is provided with screw threads 120 for connection of the petrol conduit 121. Similarly the micro switch 95 connects electrically a suitable transformer which connects to the forwardly extending high tension cables 122.

Mounted underneath the barrel 10 at the front thereof, as illustrated in FIGURES 1 and 2, is the ignition assembly 123, details whereof are best illustrated in FIGURES 5, 6, 7 and 8.

The ignition assembly 123 comprises the ignition block 124 which is bored to fit around the forward end of the barrel and be secured in position thereon in the manner illustrated in FIGURE 1. The ignition block 124 is bored and tapped on both sides to provide mounting for the insulators 125 and 126 which are held firmly against the shoulders 127 and 128, in the borings 129 and 130, by the tapped plugs 131 and 132 which are coupled in suitable manner to the high tension cables 122. The electrodes 133 and 134 extend from the insulators 125 and 126 through which they pass, to connect to the high tension cables 122 and are bent around to terminate in positions on opposite sides adjacent to the main petrol nozzle 135 which extends forwardly and upwardly from the petrol nozzle head 136 which is silver soldered into the forward end of the boring 137 which is centrally located between the borings 129 and 130. The nozzle head 136 is outwardly threaded to receive the cap piece 138 which holds in position the nozzle piece 139, of which the main nozzle 135 forms a part. As will be seen most clearly from FIGURE 6, the nozzle piece 139 consists of the disk-shaped portion 140 which is held in position between the cap piece 138 and the nozzle head 136 which

contains two small borings 141 and 142 which form the auxiliary petrol nozzles.

The main ignition nozzle 135 extends centrally from the disk-shaped portion and is substantially tubular in shape, but the flow channel therein forms a right angle near the base thereof as at 143, and in its mounted position the entrance 144 to the rear of the main ignition nozzle 135 faces upwardly. The rear of the boring 137 is tapped to receive the petrol pressure valve 145 which is provided with a screw threaded rearwardly facing extension 146 for connection to the coupling 147 at the front end of the petrol conduit 121. The petrol pressure valve 145 is bored centrally and the interior thereof is provided with the forwardly facing shoulder 148 against which the spring driven valve plunger 149 is urged by the compression spring 150. The valve plunger 149 is provided with the synthetic rubber seat 151 in its rearward end, to effect a proper seal with shoulder 148, and is formed with a plurality of longitudinally flattened faces 151 to provide flow channels for petrol past the valve plunger 149 when the same has been unseated from the shoulder 148.

The boring 137, internally threaded to receive parts 145 and 153 is provided with the rearwardly facing shoulder 154, providing a seating for the forward end of the compression spring 150. Four angularly disposed borings 155 substantially at right angles to each other are provided in the front of the part 153, for flow of petrol therethrough, when the pressure valve is open, so that a sudden rush of petrol through them will be atomized initially to provide a readily ignitable mixture issuing from the auxiliary nozzles 141 and 142 for ignition by the spark as described below.

The ignition device operates as follows:

When petrol under pressure is applied to the petrol conduit 121 the seat 151 is forced away from the shoulder 148 and petrol flows through the channels 152, through the centre of the petrol pressure valve 145, through the angularly disposed borings 155, and into the boring 137. The pressure of the petrol is relatively great and it moves through the borings 155 and forms an atomized mixture as it proceeds forward towards the nozzle with considerable speed, its momentum carrying two fine sprays of atomized petrol through the auxiliary nozzles 141 and 142 before the petrol has been able to enter the entrance 144 to the main nozzle 135, flow around the elbow 143, and reach the end of the main nozzle 135. The exceedingly fine spray issued from the auxiliary nozzles 141 and 142 mixes with the air to form a mixture which is readily ignited by the spark which extends between the electrodes 133 and 134 of the main nozzle 135, and by the time petrol issues from the main igniter nozzle 135, there is a hot flame available to ignite it so that it proceeds forward as a burning rod of petrol which is appropriately positioned to ignite the main rod of thickened flame fuel which, by that time, will be issuing from the nozzle at the forward end of the barrel 10. This ignition flame is continuous as long as the trigger is pressed.

The supply of electrical energy necessary to provide spark to ignite the petrol, the supply of petrol, the supply of gas and the supply of flame fuel are all accomplished, in connection with the flame thrower of the present invention, in well known and conventional manner so that it is not believed necessary to describe the particular means of supply herein, suitable apparatus being illustrated in the aforementioned Canadian Army Training Manual.

The completely assembled flame thrower operates as follows:

When the operator pulls the trigger rod 84 to the rear, by pulling on the arm 85, three actions take place in timed sequence.

(1) On moving to the rear, the trigger rod 84 carries with it the micro-switch actuating spindle 91 which moves the bevelled shoulder 94 against the micro switch 95, causing the latter to close an electric circuit, sending high

tension current through the high tension cables 122, up to the electrodes 133 and 134. The circuit grounds itself on the main petrol nozzle 135, creating a continual electrical spark.

(2) The nut 118 and the lock nut 117 are so adjusted on the petrol valve stem 93 that, immediately upon actuation of the micro switch 95 and establishing of the electrical spark, the face 116 contacts the front of the nut 118, moving the petrol valve stem 93 to the rear and opening the petrol valve by moving the valve head 100 off the seat 99. As previously explained, the petrol issues in very fine jets from the two auxiliary nozzles 141 and 142, and is ignited by the spark, and the ignited spray then ignites the stream of petrol which, by that time, is issuing from the main nozzle 135, producing a continuous ignition flame.

(3) The adjustable screw 87 is so adjusted that, immediately upon the creation of the ignition flame, the end 89 thereof contacts the control spindle 65, pushing the valve body 61 to the rear, shutting off supply of gas pressure to the gas cylinder 39, and opening communication between the gas cylinder 39 and the atmosphere.

This reduces the pressure against the head 36 of the pintle piston 35, and as this pressure drops, the pressure of the flame fuel within the barrel 10 of the gun, pressing on the front face of the pintle piston 35, moves the whole pintle to the rear, unseating the conical portion 31 at the front of the pintle, from the valve seat 13 of the conical nozzle component 12, and allowing the fuel to be ejected as a rod, through the nozzle tip 14. The fuel passes through the ignition flame and is ignited by it.

When the trigger rod is released by the operator, the compression springs 72 and 113 re-assert themselves, returning the trigger rod 84 to its normal position of rest, ready for another shot. In doing this the sequence of events is as follows:

The valve body 61 reseats itself, cutting off communication between the gas cylinder 39 and the atmosphere, and establishing communication with the flexible hose gas line 60, filling the gas cylinder 39 with gas under pressure, which moves the pintle 29 forward to seat the portion 31 thereof, against the valve seat portion 13 of the conical nozzle component 12, shutting off the stream of flame fuel. In moving forward, the petrol valve stem 93 seats the valve head 100 on the valve seat 99 to shut off the petrol, and at the same time the micro-switch actuating ignition control spindle 91, in moving forward, operates the micro switch to cut off the electrical current. On closing of the petrol valve 99, the petrol pressure valve 150 moves against the shoulders 148, preventing escape of the petrol within the conduit 121, so that petrol does not escape and drip from the nozzles between shots.

From the foregoing it will be seen that the action of the gun according to the invention is exceedingly simple and rapid, permitting shots to be fired in extremely rapid succession.

Normally speaking, the working pressure employed will be approximately 280 pounds per square inch, but higher or lower working pressures may be used with good results.

What I claim as my invention is:

1. In a flamethrower of the type wherein a rod of flame fuel is projectable from a nozzle at the front of a barrel to which flame fuel is supplied under pressure and wherein the projection of said rod of flame fuel is controlled by a pintle having a conical tip situated within the barrel and arranged for movement into and out of seating engagement with a conical seat in said nozzle, said flame thrower comprising electrically ignited petrol ignition means for igniting said rod of flame fuel and control means for actuating said pintle and said ignition means in timed sequence, in combination; a unitary pintle comprising; a forward portion having a conical tip thereon adapted for cooperation with the conical seat in the nozzle, and having mounted thereon a plurality of uniformly spaced apart radial vanes arranged to bear

against the inner wall of the barrel to keep said pintle axial aligned therewith; a rearward portion in axial alignment with said forward portion and united therewith, said rearward portion being more slender than said forward portion and projecting rearwardly of said barrel; and a pintle piston, having a head and a body portion, the latter portion being larger in diameter than said rearward portion of said pintle and being secured to the end of said rearward portion; a generally elbow-shaped gun body having a passage therethrough for supply of flame fuel to said barrel and formed with a rearwardly extending portion having a bore extending therethrough in axial alignment with said gun barrel and of a diameter adapted to provide a freely sliding fit with the body portion of said pintle piston; a cylinder block having a gas cylinder formed therein and secured to said rearwardly extending portion of said gun body with said gas cylinder in axial alignment with the bore therein, said gas cylinder being of suitable diameter to provide a sliding fit around the head of said pintle piston; and means, including a gas port formed in said cylinder block for supplying gas under pressure to said gas cylinder rearwardly of the head of said pintle piston and exhausting gas under pressure therefrom; the length of said pintle piston being such that when the conical tip of the forward portion of the pintle is seated in said conical seat, the head of said pintle piston is in the forward end of said gas cylinder.

2. The combination defined in claim 1 including a recess in said bore to accommodate an oil sealing ring, and an oil sealing ring seated therein which wipes the surface of the body portion of the pintle piston to seal the flame fuel in the barrel against escape to the rear.

3. The combination defined in claim 2 including a gas sealing washer on the head of the pintle piston adapted to prevent passage of gas between the surface of the gas cylinder and the pintle piston head, and vent means at the front end of the gas cylinder communicating the interior thereof to the atmosphere.

4. The combination defined in claim 1, including at least one recoil washer within the rearward end of the gas cylinder.

5. The combination defined in claim 1 in which said means for supplying gas under pressure to said gas cylinder rearwardly of the head of said pintle piston and exhausting gas under pressure therefrom comprises; a control block secured to a side of said cylinder block, said control block having a bore therein extending from the forward end thereof part way through said control block in a direction generally parallel to the axis of the gas cylinder, said bore having an enlargement at the forward end thereof, said control block having a gas port arranged to lie in register with the gas port in said cylinder block leading to the rearward end of said bore and a gas supply port adapted for connection to a supply of gas under pressure leading into a central portion of said bore; a valve body having a hollow centre and axially slidably within said bore, said valve body being formed with a disc shaped valve head at the forward end thereof, centrally positioned port means affording communication between the periphery of said valve body and the hollow centre thereof and radial vents affording communication between the hollow centre of said valve body and the forward end of the annular space formed between the walls of said enlargement of said bore and the periphery of said valve body; a plug secured in the forward end of said bore, said plug having a central passage therein vented substantially radially to the atmosphere and having an axially disposed bushing of smaller diameter than said central passage at the forward end thereof and being provided at its rearward end with an annular valve seat for said disc shaped valve head; a valve stem axially slidably in said bushing, united to said valve head and extending through said bushing forwardly thereof; spring means urging said valve body forward to a position in which said valve head is seated on said

60 communication between the periphery of said valve body and the hollow centre thereof and radial vents affording communication between the hollow centre of said valve body and the forward end of the annular space formed between the walls of said enlargement of said bore and the periphery of said valve body; a plug secured in the forward end of said bore, said plug having a central passage therein vented substantially radially to the atmosphere and having an axially disposed bushing of smaller diameter than said central passage at the forward end thereof and being provided at its rearward end with an annular valve seat for said disc shaped valve head; a valve stem axially slidably in said bushing, united to said valve head and extending through said bushing forwardly thereof; spring means urging said valve body forward to a position in which said valve head is seated on said

annular valve seat, said centrally positioned port means on said valve body being so positioned as to register with said gas supply port when said valve head is so seated; and means for displacing said valve stem to the rear against the pressure of said spring means simultaneously to cut off said gas supply port and unseat said valve head from said annular valve seat to establish communication between the hollow centre of said valve body and the atmosphere.

6. The combination defined in claim 5 in which said control block includes a second boring passing completely therethrough from front to rear and said means for displacing said valve stem to the rear comprises a trigger rod slideable within said second boring, an arm secured to the front end of said trigger rod, and a contact member mounted on the end of said arm and in axial alignment with said valve stem and arranged on withdrawal of said trigger rod to the rear to contact said valve stem and carry it to the rear.

7. The combination defined in claim 6 in which said trigger rod is coupled to actuating means for the ignition means.

8. The combination defined in claim 7 including a longitudinally slideable spindle mounted parallel to said trigger rod; means connecting said spindle to said trigger rod whereby said trigger rod and said spindle may be moved rearwardly as a unit; a micro-switch electrically connected in a high tension circuit forming a part of said electrically actuated petrol ignition means and mounted in operative association with said spindle, said spindle having means arranged to engage an actuating member of said micro-switch upon movement of said spindle to the rear.

9. The combination defined in claim 8 in which said spindle has a longitudinal boring, and said combination further comprises a petrol valve for controlling supply of petrol to said ignition means mounted in alignment with said spindle forwardly thereof in a fixed part of said flamethrower, said petrol valve comprising a petrol inlet port and a petrol outlet port, said outlet port leading forwardly of said petrol valve and comprising a rearwardly facing annular valve seat; a valve head arranged for co-operation with said valve seat; a valve stem united to said valve head and passing through said boring in said spindle to project to the rear thereof; means carried by the rearwardly projecting end of said valve stem for contacting the end of the spindle whereby the valve stem and valve head will be carried rearwardly with said spindle; said means on the end of said valve stem being axially spaced apart from the end of said spindle, and being axially adjustable whereby the time of opening of said petrol valve relative to the time of actuation of said

micro-switch as said spindle is moved rearwardly may be adjusted; and spring means urging said valve stem forwardly with respect to said spindle.

10. The combination defined in claim 9 in which said control block includes a depending portion and said petrol valve is positioned therein.

11. In a flamethrower of the type wherein a rod of flame fuel is projectable from a nozzle at the front of a barrel to which flame fuel is supplied under pressure and wherein the projection of said rod of flame fuel is controlled by a pintle having a conical tip situated within the barrel and arranged for movement into and out of seating engagement with a conical seat in said nozzle, said flame thrower comprising electrically ignited petrol ignition means for igniting said rod of flame fuel and control means for actuating said pintle and said ignition means in timed sequence, in combination; ignition means comprising a body portion secured beneath the barrel of the flamethrower at the forward end thereof, said body portion having a boring formed therein substantially parallel to said barrel; means for supplying petrol under pressure to the rear end of said boring; secured within said boring a plug formed with a plurality of outwardly directed atomizer passages therethrough; jet means secured in the forward end of said boring, said jet means comprising a centrally located forwardly directed main jet nozzle consisting essentially of a tube extending forwardly of said body portion and having a flow channel passing up the centre thereof and having a radially disposed inlet port opening into the interior of said boring; and said jet means having two secondary jet passages of very small diameter disposed parallel to said main jet nozzle in proximity thereto; electrical ignition means including two electrodes disposed to provide a spark gap on either side of said main jet nozzle intermediate the ends thereof; and means for supplying high tension electricity to said electrical ignition means.

12. The combination defined in claim 11 including a pressure valve mounted in said boring rearwardly of said plug, said pressure valve being arranged to allow passage of petrol to said jet means only when the pressure thereof exceeds a predetermined value.
